UNITED STATES PATENT OFFICE.

EDGAR ALLAN PETRIE, OF BERWICK, LOUISIANA.

WAGON-JACK.

SPECIFICATION forming part of Letters Patent No. 700,367, dated May 20, 1902.

Application filed October 21, 1899. Serial No. 734,344. (No model.)

To all whom it may concern:

Be it known that I, EDGAR ALLAN PETRIE, a citizen of the United States, residing at Berwick, in the parish of St. Mary and State of Louisiana, have invented a new and useful Wagon-Jack, of which the following is a specification.

My invention relates to lifting-jacks, and has for its object to provide a cheap, simple, and durable jack which can readily be operated with the minimum amount of power.

With this object in view my invention consists in a vertical standard slotted and carrying a sliding bar adapted to be raised and lowered by a curved lever fulcrumed on the standard and connected thereto by means of a link and pin, the pin sliding in the slot in the standard.

My invention further consists in such parts and combinations of parts, all of which will be fully described hereinafter, pointed out in the claim, and illustrated in the accompanying drawings, in which—

Figure 1 is a side elevation of my invention complete. Fig. 2 is a similar view looking from the rear. Fig. 3 is an end view, and Fig. 4 is a cross-section through the standard and lifting-bar.

Referring now more particularly to the drawings by reference-numerals, 5 indicates a suitable base, on which is secured the standard 6, provided with side flanges 7 and 8 to form a dovetailed groove, in which the lifting-bar 9 is slidably secured, the edges of said bar being beveled to register with the inner walls of said flanges. This sliding bar is provided with a slideable head 10, adjustably held on said bar by a pin 11 engaging in the perforations 12.

Secured on the bar 9 and projecting through the slot 13 is a pin 14, engaged by one end of the link-bar 15, while to the other end of the link-bar a curved lever 16 is secured at 17. Said lever is fulcrumed to the standard at 18.

The slot 13 extends entirely to the bottom of the standard, thereby forming two legs, the lower end of each of which is bent laterally and perforated to form a foot by means of which the standard is secured to the base.

One of the feet is bent in one direction, as under the bar 9, and the other one is bent in the opposite direction. This construction of

the lower end of the standard gives it a good substantial support and at the same time renders it possible for a blacksmith to make 55 the jack without special tools, as the lower end of the standard can be easily split to form the slot and the ends of the legs bent laterally to form the feet.

To add rigidity to the standard, a brace-bar 19 is secured thereto at the pivot-point of curved lever and to the base 5. To permit of the link passing the upper end of the brace and the bolt for securing it in position, the intermediate portion of the link is bent or bowed 65 outwardly, as shown in Fig. 3.

The operation of my invention is as follows: All the parts being assembled, the handle of the curved lever is grasped and pushed down until the link-bar assumes a vertical position, 70 thus raising the lift-bar, and by reason of the curved end of the lever the center of gravity will be thrown slightly to the right of the pivot-point thereof, which will cause the parts to remain in the desired position until the 75 lever is again raised.

The head can be adjusted to suit a variable number of heights through the medium of the pin and perforations in the lift-bar.

Having thus fully described my invention, 80 what I claim as new, and desire to secure by Letters Patent, is—

A lifting-jack comprising in combination a base 5, carrying a standard 6, provided with side flanges 7 and 8, the lifting-bar 9 slidably secured between the said flanges, the edges of said bar being beveled to correspond with the inner walls of said flanges, the slideable head 10 adjustably held on the said bar 9, the pin 11 for securing the head, said pin engaging the perforation 12, the pin 14 secured upon the bar 9 and projecting through the slot 13, said pin 14 engaging the link-bar 15 at one end and the curved lever 16 secured to the said link-bar at 17, said lever being 90 fulcrumed to the standard at 18, and the brace-bar 19 connecting the standard and base, and all arranged and adapted to operate substantially as shown and described.

EDGAR ALLAN PETRIE.
